COAXIAL STUB SUPPORTS

Robert B. Muchmore, Pacific Palisades, Calif., assignor to Sperry Rand Corporation, a corporation of Delaware

Application February 20, 1952, Serial No. 272,636

15 Claims. (Cl. 333—97)

This application is a continuation-in-part of application S. N. 772,288 filed September 5, 1947, now abandoned, and entitled, "Coaxial Stub Supports."

The present invention relates to ultra high frequency energy transmission line systems, and, more particularly, it is concerned with methods and apparatus for increasing the frequency operating range of stub supports used in such transmission line systems.

Heretofore coaxial lines have employed two general types of supports for the inner conductor, namely, dielectric beads spaced at intervals along the conductor, or quarter wavelength shorted stub sections of coaxial line. While bead-supported lines are adequate at radio frequencies, they start to introduce appreciable discontinuities in the line in the ultra-high frequency range. If the beads are evenly spaced at intervals sufficiently close to give good support, as in the conventional bead-supported line, where the frequency of the transmitted energy is such that the distance between the beads is of the order of half a wavelength, or integral multiple thereof, the mismatch and reflection introduced by each bead becomes additive along the line. Beads can be used at ultra-high frequencies if care is taken to properly space or group the beads to prevent the reflected energy at each bead from adding in phase with energy reflected from other beads. However, such spacing or grouping makes the bead-supported line frequency-sensitive, any variation in frequency changing the effective spacing of the beads in terms of wavelength.

To provide a coaxial line which functions efficiently at frequencies of the order of 1,000 to 3,000 megacycles per second, the shorted coaxial line stub support is preferred because it introduces substantially no loss at the frequency where its length is exactly a quarter wavelength. Thus in the coaxial stub support no consideration need be given to the spacing of the stubs as is necessary in the bead-supported line.

However, although there are no dielectric losses in such stub supports, the use of the stub-supported coaxial line is likewise limited in operating frequency range since the input impedance of the stub support changes with a change in operating frequency. At frequencies different from the design frequency, the stub is no longer a quarter wavelength device, and consequently introduces a low susceptance which shunts the main transmission line, this shorting susceptance causing standing waves which in turn reduce the power capacity and efficiency of the line.

One method heretofore proposed to extend the frequency range of a stub-supported coaxial line is achieved by enlarging the center conductor of the line for a distance of a quarter-wavelength on each side of the stub support junction. Such a compensated stub support is described in Patent No. 2,446,982 issued August 10, 1948 to R. V. Pound. Although the operating range of frequencies is improved by changing the diameter of the inner conductor in the region of the stub support, the practical band width is still only of the order of 40% of the design frequency.

2

It is the general object of this invention to avoid and overcome the foregoing and other difficulties in and objections to the prior art practices by the provision of a compensated stub support which is characterized by its low attenuation and low standing wave ratio over a greatly extended band of frequencies in the ultra-high frequency band.

It is another object of this invention to provide a coaxial stub support which provides a broad band operation of the order of 100% band width at operating frequencies of the order of 2,000 megacycles.

Another object of this invention is the provision of a support for the inner conductor of a coaxial line which introduces minimum reflection over a broad band of frequencies and which may be spaced at any desired intervals along the coaxial line.

These and other objects of the invention which will become apparent as the description proceeds are achieved by the provision of a stub-supported coaxial transmission line system comprising a main section of coaxial transmission line having an inner conductor and an outer conductor, the inner conductor being supported by stub sections of coaxial line oriented at right angles to the main section and having inner and outer conductors connected respectively to the inner and outer conductors of the main section, the stub sections each having a length equal to a quarter wavelength at the design frequency and being short circuited at their free ends. A pair of open-ended line sections each having a length equal to a quarter wavelength at the design frequency are connected in series with the inner conductor of the main section in the region of each stub section, the open-ended line sections being disposed on opposite sides of the junction of the stub support along the main section. Each open-ended line section is spaced from the junction by distance along the main section of a quarter wavelength at the design frequency. In addition, the admittance of the main section is increased in the region intermediate the pairs of open-ended line sections, preferably by increasing the diameter at the inner conductor.

A better understanding of the invention may be had by reference to the accompanying drawings, wherein:

Fig. 1 is a cross-sectional view of the preferred form of the invention;

Figs. 2, 3, 4 and 5, are circle diagrams used in the explanation of the present invention; and

Fig. 6 is a graphical plot of the voltage standing wave ratio as a function of frequency of a coaxial line system employing the features of the present invention.

With particular reference to the embodiment of the invention illustrated in Fig. 1, the numeral 10 indicates generally a coaxial transmission line having an inner conductor 12 and a concentric outer conductor 14. The inner conductor 12 is supported from the outer conductor by means of a compensated T-stub support indicated generally at 16, the support incorporating the novel features of the present invention as hereinafter described.

The T-stub support includes a quarter wavelength long coaxial line stub section 18 terminated at one end by a shorting disc 20 which rigidly maintains the inner conductor 22 and outer conductor 24 of the stub section in concentric relationship. The outer conductor 24 of the stub section 18 is joined at right angles to the outer conductor 14 of main coaxial line 10. The inner conductor 22 of the stub section 18 is joined at right angles to the midpoint of a half wavelength long enlarged inner conductor section 26. It is to be understood that the wavelength in determining the length of the stub section 18 and enlarged inner conductor section 26 is the wavelength of an electromagnetic wave in free space at the center frequency of the band of frequencies over which the T-stub support is to operate. This center frequency is

commonly referred to as the design frequency of the system.

The present invention further provides a pair of open-circuited line sections 28 and 30 which are connected in series with the inner conductor 12 of the coaxial line 10. The open-circuit line sections are effectively positioned adjacent to the ends of the enlarged inner conductor section 26.

One method of constructing the open-circuit line sections is illustrated in Fig. 1, in which the ends of the enlarged conductor section 26 are each provided with an axially extending bore 32 into which is inserted a reduced diameter portion 34 of the adjoining end of the inner conductor 12. Insulating sleeves 36 made of polystyrene or other suitable dielectric material, secure the portions 34 concentrically within the bores 32 to provide a rigid mechanical coupling therebetween. Dielectric discs 38 and washers 40 are provided in each joint to insulate the enlarged inner conductor section 22 from the adjoining inner conductor 12 of the main coaxial line 10.

Thus the reduced diameter portion 34, the bore 32, and dielectric sleeve 36 combine to form an open-circuit coaxial line section in series with the inner conductor 12 on either side of the enlarged inner conductor section 26. The length of the series coaxial line sections 28 and 30 is a quarter wavelength. However, since these open-circuited line sections are dielectric filled, the wavelength used in calculating the length of these sections is based on the wavelength of an electromagnetic wave in the dielectric medium at the design frequency, the relationship between the wavelength λ_0 in free space to the wavelength λ_1 in the dielectric-filled line being given by the equation

$$\lambda_0 = \lambda_1 \sqrt{\mu}$$

where μ is the dielectric constant. The wavelength for a polystyrene-filled coaxial line is approximately 0.6 the wavelength in free space while the wavelength of an air-filled coaxial line is equal to the wavelength in free space. Because the quarter wavelength dielectric-filled open-circuit line sections are thus physically shorter than a quarter wavelength coaxial line section filled with air, the open-circuit line sections can be effectively folded within the half wavelength long enlarged inner conductor section 26 to provide a compact and structurally rugged support.

By way of illustration, a physically practical stub support incorporating the features above described which provides a theoretical band width of better than 100% of the design frequency has the following properties:

With a main coaxial line section having a characteristic impedance of 70 ohms, the section of the coaxial line embodying the enlarged inner conductor section 26 is designed to have a characteristic impedance of 50 ohms, the coaxial line stub is designed to have a characteristic impedance of 45 ohms, and the open-circuit line sections are each designed to have a characteristic impedance of 27.5 ohms. While a T-stub support having these characteristic impedances for the various components of the support does not necessarily represent the optimum which may be achieved in a broad band support incorporating the features of the invention, it does represent a physically practical support which can be readily constructed and which gives more than twice the band width heretofore achieved using the shorted T-stub supports with half wavelength transformers.

The operation of the T-stub support described above may be more clearly understood through the study of impedance circle diagrams as shown in Figures 2, 3, 4 and 5. Such circle diagrams are widely used for simple graphical analysis of transmission line behavior. The complete detailed description of the nature and use of such diagrams may be found on pages 22 through 33 of the book "Microwave Transmission" of J. C. Slater, first

edition 1942, McGraw Hill Book Company, New York and on pages 689 through 693 of an article entitled "Graphical Solution of Voltage and Current Distribution and Impedance of Transmission Lines" by R. C. Paine, in the Proceeding of the Institute of Radio Engineers, volume 32, November, 1944. Since the use of the impedance circle diagram is so well established, a repetition of the full description is believed to be unnecessary.

The circle diagram is employed here to show the change in impedance of the load produced by the transmission line section in the region of the support 16 with respect to the electrical length of the section to ascertain how the load produced by the support matches the characteristic impedance of the main coaxial line 10 at frequencies other than the design frequency. It will be appreciated that at the design frequency, the stub 18 introduces no shunting susceptance, the enlarged conductor section 26 being exactly half a wavelength long introduces no reflections, and the open-circuit line sections have zero impedance, so that a perfect match between the support and the line is achieved.

The circle diagram of Figure 2 is a plot of the load impedance of the support at a frequency of .6 of the design frequency. In the circle diagram the reactance is plotted along the ordinate axis and resistance is plotted along the abscissa axis, both the reactance and resistance being normalized with respect to the characteristic impedance of the transmission line whose characteristics are to be investigated. Superimposed on the rectangular coordinate graph there is a first series of circles having centers on the ordinate axis, each of these circles intersecting the abscissa axis at the point (1, 0) and representing a constant electrical distance, β_1 in degrees, along the transmission line. Portions of two such constant β_1 circles are shown at 42 and 44.

A second series of circles, having centers on the abscissa axis, are provided which are mutually orthogonal with the first series of circles and which surround the point (1, 0) on the abscissa axis. Each of these second series of circles intersects the abscissa axis at mutually reciprocal points, thus forming a family of eccentric circles. Two such circles are shown at 46 and 48 by way of illustration.

The significance of the family of eccentric circles is as follows: If the point (1, 0) is taken to represent the normalized characteristic impedance of any transmission line and the line is terminated by a load impedance which is different than the characteristic impedance of the line, the input impedance of the line at any arbitrary point on the line will fall somewhere on the particular eccentric circle passing through the point on the rectangular coordinate graph corresponding to the normalized load impedance.

The impedance along the transmission line in the region of one of the supports of the present invention, where the frequency is .6 of the design frequency for example, may be plotted by starting at the point a at which point the impedance is that of the characteristic impedance of the transmission line, which is 70 ohms in the present illustrative example. The characteristic impedance of the transmission line, which for the convenience of plotting is normalized with respect to the 50 ohm characteristic impedance of the enlarged conductor section 26 of the support, therefore 1.4, which is plotted at point a (1.4, 0) on the circle diagram of Figure 2.

The impedance of the open-circuit line section 28, which is in series with the transmission line at a point a , is next added to the impedance of the line as the impedance is plotted moving along the section of the line in the region of the support. The open-circuit line section 28 has a normalized capacitive reactance of .4, which, when added to the impedance of the line, brings the plot on the chart of Figure 2 to a point b , whose coordinates are (1.4, -0.4).

The combined impedance of the line and the open-circuit line section is transformed along the enlarged conductor section 26 to the T-stub junction, which on the chart brings the plot to the point *c* by following the appropriate eccentric circle 46 passing through the point *b* through an arc of extent corresponding to .6 of a quarter wavelength, or 54°, proceeding in the clockwise direction.

In order to then be able to add the inductive susceptance of the shunt-connected stub, the impedance at point *c* must be inverted to the corresponding admittance value. This is accomplished on the chart by following on around the eccentric circle 46 passing through points *b* and *c* an additional arc length equivalent to a quarter wavelength, or 90 electrical degrees on the chart, to the point *d*. The inductive susceptance of the stub, which has a normalized value of .81, is then added to the admittance at point *d* which brings the plot to point *e*.

Inverting the admittance at point *e* back to the corresponding impedance value by following the eccentric circle 46 passing through the point *e* a distance of 90 electrical degrees on the chart brings the plot to the point *f*. Further translation clockwise along this circle a distance of 54 electrical degrees on the chart, transforms the impedance at the point *e* along the enlarged inner conductor section 26 to the point where the open-circuit line section 30 is positioned, which brings the plot to the point *g*. Addition of the impedance of the open-circuit line section 30 completes the plot to the point *h*. In the plot of Fig. 2, the lines *a*—*b*, *d*—*e*, and *g*—*h* actually are coincident but have been separated slightly to present a clearer picture of the manner in which the graph is plotted.

It will be noted that the point *a* and point *h* are the same and that in following around the plot of the impedance of the transmission line section from one end of the T-stub support to the other that the plot completely closes, which means that the input impedance of the line looking in at the left end of the T-stub support is identical to the impedance of the line looking to the right from the other end of the T-stub support, and that there is a perfect match of the T-stub support to the transmission line at .6 of the design frequency.

Fig. 3 is a plot similar to Fig. 2 of the impedance of the load produced by the transmission line section in the region of the support at a frequency of .8 of the design frequency. It will be noted that at this intermediate frequency the point *h* representing the input impedance does not quite fall back on the point *a*, which indicates that the impedance of the line at one end of the T-stub support does not match exactly the impedance of the line at the other end of the T-stub support looking in the same direction. However, the mismatch at this intermediate frequency is relatively small and produces a VSWR which is well within practical design limits.

Fig. 4 is a similar plot at a frequency of .5 the design frequency, again showing that the impedance of the T-stub support substantially matches the characteristic impedance of the line, as indicated by the close proximity of the points *a* and *h*.

The graphical plot of Fig. 5 is similar to that of Fig. 2 but at a frequency of 1.5 times the design frequency. It will be noted that the reactance of the open-circuit line sections is inductive so that point *b* is above the abscissa axis. As before the impedance at point *b* is transformed in a clockwise direction along an eccentric circle a distance of 1.5 times a quarter wavelength, or 135 electrical degrees on the chart, to a point *c* and inverted to the point *d*. The inductive susceptance of the stub is then added to bring the plot to point *e*. Again inverting back to impedance brings the graphical plot to point *f* and transforming through 135° brings the plot to point *g* where the inductive reactance of the sec-

ond open-circuit line section is added to complete the plot to point *h*. The similarity between Figs. 4 and 5 is believed evident, Fig. 5 being substantially identical to Fig. 4 inverted about the abscissa axis.

A plot of VSWR, which is a measure of the absolute magnitude of mismatch between the points *a* and *h* at any given frequency, as a function of frequency is shown in Fig. 6. On a linear scale of frequency, the curve of Fig. 6 is symmetrical about the design frequency. The dotted line curve of Fig. 6 is a plot on the same scale of the prior art stub support having a half wavelength transformer in series with the inner conductor at the point of the stub. The resulting band width over which substantial match of the T-stub support to the line is achieved thus extends at least from the .5 to 1.5 of the design frequency, or a band width of at least 100%, which represents a considerable improvement over the band width of heretofore known T-stub supports for coaxial lines.

From the above description it will be recognized that the objects of the invention are met by the provision of a support for the inner conductor of a coaxial transmission line having a broad band operation which is more than double the best results of the prior art practice in the use of compensated stubs. Furthermore the stub support of the present invention can be used in a line for transmitting frequencies in a range in which dielectric bead-supported lines become inefficient and frequency-sensitive.

While conceivably the compensating series impedance of the T-stub support of the present invention may be physically incorporated in other ways, as by folding the open-circuit line sections outwardly along the conductor instead of inwardly toward the junction with the stub section, the preferred form illustrated provides a mechanically rugged and practical stub supported construction. Also the description of the invention has been in terms of a support for a coaxial line, but the invention may equally well be considered as a filter having broad band-pass properties, in which case, the support feature no longer being essential, the principles of the invention may be applied to parallel two-wire line systems as well as coaxial line systems.

Since many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A stub-supported transmission line comprising a main section of coaxial transmission line having an inner conductor and an outer conductor adapted to transmit frequencies higher and lower than a design frequency, a stub section of coaxial transmission line having an inner and outer conductor connected respectively to the inner and outer conductors of the main section in substantially perpendicular relationship, the stub section having an electrical length of substantially a quarter wavelength at the design frequency and being shorted at its free end, the inner conductor of the main section having an enlarged diameter portion adjacent the point of junction with the inner conductor of the stub section and extending an electrical distance of a quarter wavelength at the design frequency in both directions from said junction, a pair of open-circuit line sections connected in series with the main section and spaced apart at their series connection points by an electrical distance of half a wavelength at the design frequency, the open-circuit line sections including reduced diameter portions on the inner conductor of the main section concentrically extending into a bore in each end of the enlarged diameter portion, and sleeves of insulating ma-

terial between the bores and reduced diameter portions for securing the adjacent inner conductor portions in open-circuit relationship, the open-circuit line sections having an electrical length of substantially a quarter wavelength at the design frequency.

2. A stub-supported transmission line comprising a main section of coaxial line having inner and outer conductors adapted to transmit frequencies higher and lower than a design frequency, a stub section of coaxial transmission line having inner and outer conductors connected respectively to the inner and outer conductors of the main section in substantially perpendicular relationship, the stub section having an electrical length of substantially a quarter wavelength at the design frequency and being shorted at its free end, the inner conductor of the main section having an enlarged diameter portion adjacent the point of junction with the inner conductor of the stub section and extending an electrical distance of a quarter wavelength at the design frequency in both directions from said junction, and a pair of open-circuit line sections connected in series with the inner conductor of the main section of coaxial transmission line adjacent the ends of the enlarged diameter portion, each open-circuit line section having an electrical length of substantially a quarter wavelength at the design frequency.

3. A stub-supported transmission line comprising a main section of coaxial transmission line having inner and outer conductors adapted to transmit frequencies higher and lower than a design frequency, a stub-section of coaxial transmission line having inner and outer conductors connected respectively to the inner and outer conductors of the main section in substantially perpendicular relationship, the stub section having an electrical length of substantially a quarter wavelength at the design frequency and being shorted at its free end, the inner conductor of the main section having an enlarged diameter portion adjacent the point of junction with the inner conductor of the stub section and extending an electrical distance of a quarter wavelength at the design frequency in both directions from said junction, and a pair of open-circuit line sections connected in series with the main section, said sections having their series connection points with said main section respectively positioned on either side of said junction by an electrical distance of a quarter wavelength at the design frequency, each open-circuit line section having an electrical length of substantially a quarter wavelength at the design frequency.

4. A stub-supported transmission line comprising a main section of coaxial transmission line having inner and outer conductors adapted to transmit frequencies higher and lower than a design frequency, a stub section of coaxial transmission line having inner and outer conductors connected respectively to the inner and outer conductors of the main section in substantially perpendicular relationship, the stub section having an electrical length of substantially a quarter wavelength at the design frequency and being shorted at its free end, and a pair of open-circuit line sections connected in series with the main section and disposed on opposite sides of the junction between the stub section and the main section, the open-circuit line sections being spaced from said junction at their series connection points by an electrical distance of a quarter wavelength at the design frequency, each open-circuit line section having an electrical length of substantially a quarter wavelength at the design frequency.

5. A stub-supported transmission line comprising a main section of coaxial transmission line having inner and outer conductors adapted to transmit frequencies higher and lower than a design frequency, a stub section of coaxial transmission line having inner and outer conductors connected respectively to the inner and outer conductors of the main section in substantially perpendicular relationship, the stub section having an electrical length of substantially a quarter wavelength at the design frequency and being shorted at its free end, and a pair

of two-conductor resonant line sections, the two conductors of each resonant line section being connected at the corresponding ends thereof in series with one of the conductors of said main section, the series connection points between said resonant line sections and said main section being respectively positioned at a quarter wavelength distance from and on opposite sides of the junction between the stub section and the main section, the resonant line sections having an electrical length of substantially a quarter wavelength at the design frequency.

10 6. A coaxial transmission line system comprising a main coaxial line section, a short-circuited coaxial line section connected in shunt with the main line section, a pair of open-ended coaxial line sections connected in series with one of the conductors of the main line section respectively on each side of the junction of the short-circuited line section and main line section at an electrical distance of a quarter wavelength at the design frequency of the line, the short-circuited and open-circuited coaxial line sections having an electrical length of a quarter wavelength at the design frequency, and means for increasing the characteristic admittance of the main line section in the region intermediate the junctions of the open-ended line sections and the main line section.

15 7. A coaxial transmission line system comprising a main coaxial line section, a short-circuited coaxial line section connected in shunt with the main line section, and a pair of open-ended coaxial line sections in series with one of the conductors of the main line section connected respectively on each side of the junction of the short-circuited line section and main line section at an electrical distance of a quarter wavelength at the design frequency of the line, the short-circuited and open-circuited coaxial line sections having an electrical length of a quarter wavelength at the design frequency.

20 8. A coaxial transmission line system comprising a main coaxial line section, a short-circuited coaxial line section connected in shunt with the main line section, the short-circuited coaxial line section having an electrical length of a quarter wavelength at the design frequency, a pair of resonant line sections in series with one of the conductors of the main line sections connected respectively on each side of the junction of the short-circuited line section and main line section at an electrical distance of a quarter wavelength at the design frequency of the line, and means increasing the admittance of the main line section in the region intermediate the junctions of the resonant line sections and the main line section.

25 9. A coaxial line system for ultra high frequency energy comprising a main section of coaxial transmission line having an inner and an outer conductor, a short-circuit stub section of coaxial transmission line having an inner and an outer conductor connected at one end respectively to the inner and the outer conductor of the main section and connected together at their opposite ends, and a pair of open-circuit stub sections of coaxial transmission line each connected at one end thereof in series with one of the conductors of the main section of transmission line, the points of series connection of the open-circuit stub sections being displaced in opposite directions along the main section from the point of junction with the short-circuit stub section, the physical lengths of the short-circuit stub section, the open-circuit stub sections, and the line sections between the connecting point of the short-circuit stub section and respective open-circuit stub sections all being related to each other in inverse proportions to the square roots of the dielectric constants of the respective coaxial line sections, the characteristic impedance of the portion of the main section of coaxial transmission line between the points of series connection of the open-circuit stub sections being appreciably lower than the remaining portions of the main sections.

30 10. A coaxial line system for ultra high frequency energy comprising a main section of coaxial transmission line having an inner and an outer conductor, a short-

circuit stub section of coaxial transmission line having an inner and an outer conductor connected at one end respectively to the inner and the outer conductor of the main section and connected together at their opposite ends, and a pair of open-circuit stub sections of coaxial transmission line each connected at one end thereof in series with one of the conductors of the main section of transmission line, the points of series connection of the open-circuit stub sections being displaced in opposite directions along the main section from the point of junction with the short-circuit stub section, the physical lengths of the short-circuit stub section, the open-circuit stub sections, and the line sections between the connecting points of the short-circuit stub section and respective open-circuit stub sections all being related to each other in inverse proportion to the square roots of the dielectric constants of the respective coaxial line sections.

11. A two-conductor line system comprising a main section of two-conductor transmission line, a short-circuit stub section of two-conductor transmission line connected at one end across the main section of transmission line and being shorted at the other end, and a pair of open-circuit stub sections of two-conductor transmission line each connected at one end thereof in series with one of the conductors of the main section of transmission line, the points of series connection of the open-circuit stub sections being displaced in opposite directions along the main section from the point of junction with the short-circuit stub section, the physical lengths of the short-circuit stub section, the open-circuit stub sections, and the line sections between the connecting point of the short-circuit stub section and respective open-circuit stub sections all being related to each other in inverse proportion to the square roots of the dielectric constants of the respective line sections.

12. A coaxial transmission line system comprising a main coaxial line section having inner and outer conductors, a short-circuit coaxial line section connected in shunt with the main line section, the short-circuit line section having an electrical length of a quarter wavelength at the design frequency, and a pair of two-conductor resonant line sections, one of the conductors of the main section having an intermediate portion adjacent the junction with the short-circuit line section and insulated from the rest of the main section at points a quarter wavelength on either side of said junction, the two conductors of each of the resonant line sections being connected at their corresponding ends to said one conductor of the main section on either side of said insulated points, whereby the resonant line sections are series connected between said insulated portion and the rest of said one conductor of the main section.

13. A coaxial transmission line comprising a main coaxial line section, a quarter wavelength long short-circuit coaxial line section connected in shunt with the main line section, and a pair of two-conductor resonant line sections connected with adjacent ends of the conductors connected in series with one of the conductors of the main section, the series connection points between the respective resonant line sections and said one conductor of the main section being positioned respectively on each side of the junction of the short-circuit line section and the main line section.

14. A two-conductor line system comprising a main section of two-conductor transmission line, a first resonant two-conductor line section having adjacent ends of the two conductors connected in shunt across the two conductors of the main section, second and third resonant two-conductor line sections having adjacent ends of the two conductors connected in series with one of the two conductors of the main section, the series junction points between the main section and said second and third resonant line sections being respectively positioned a quarter wavelength on either side of the junction of the main section with the first resonant line section.

15. A stub-supported transmission line comprising a main section of coaxial line having inner and outer conductors adapted to transmit frequencies higher and lower than a design frequency, a stub section of coaxial transmission line having inner and outer conductors connected respectively to the inner and outer conductors of the main section in substantially perpendicular relationship, the stub section being shorted at its free end, the inner conductor of the main section having an enlarged diameter portion adjacent the point of junction with the inner conductor of the stub section, and a pair of open-circuit line sections connected in series with the inner conductor of the main section of coaxial transmission line adjacent the ends of the enlarged diameter portion, the physical lengths of the short-circuited stub section, the open-circuited stub sections, and the line sections between the short-circuited stub section and the respective open-circuit stub sections being related to each other in inverse proportions to the square roots of the dielectric constants associated with the respective sections.
